RECIPROCABLE ACTUATOR DEVICE

Sidney Weiser, Plainview, N. Y., assignor to Federal Manufacturing & Engineering Corporation, a corporation of New York

Application October 18, 1955, Serial No. 541,129

8 Claims. (Cl. 242—55)

The invention relates to actuator devices, and relates more particularly to such devices that can actuate a reciprocable linear movement.

The invention has among its objects to provide such a device that will work with a minimum power requirement for a given load, and which will be powered throughout the entire path in either direction, and will arrest the movement at the end of the path in either direction free from any rebound.

The invention is applicable for use in connection with the reciprocation of the shifting part of a photographic slide changer employed in connection with a projector. The invention will be described in connection with such a slide changer, but it will be understood that this is merely for the purpose of illustration, and that no limitation is intended thereby as the device may be put to many other uses.

Further objects and advantages of the invention will be set forth in part in the following specification and in part will be obvious therefrom without being specifically referred to, the same being realized and attained as pointed out in the claims hereof.

In the accompanying drawings.

Fig. 1 is a schematic side elevational view of the device in accordance with the invention applied to a slide changer in a photographic projector;

Fig. 2 is a front elevational view of the device, with the cover removed, partly in section; and

Fig. 3 is an under-side plan view, as seen in direction 3—3 of Fig. 1, but with the cover still removed.

In carrying the invention into effect in one of the embodiments which has been selected for illustration in the accompanying drawings and for description in this specification, and referring now particularly to Fig. 1, the actuator device 11 is applied to the shifting part 12 of a slide changer 13 that is installed on a photographic projector 14.

In view of the exemplified application to a slide changer referred to, the device 11 is shown suspended with the base plate 16 on top and the removable cover or housing 17 disposed below the plate 16. It will, of course, be obvious to those skilled in the art that the device 11 can also be mounted in any other manner for other uses.

The base plate 16 may be placed below the under-side of the shiftable part 12 by well-known conventional means, for instance by means of a bracket 18 that is connected to the base plate 16 and which is removably secured to the frame of the slide changer 13. On the shifting part 12 there may be mounted a pin 19 that is received in a reciprocating element of the actuator device, for instance an elongated slider 21 that projects from the plate 16 and which has a recess 22 that engages the pin 19. Thereby, reciprocation of the slider 21 will be imparted to the pin 19 and this to the shifting part 12. The path of the reciprocation of the slider 21 is in the instant exemplification so dimensioned that it coincides with the length of the stroke of the shifting part 12. The

2

shifting part 12 is movable between a projecting position (shown in solid lines in Fig. 1) wherein it holds a slide in register with the optical axis of the projector 14 and, respectively, a retracted position (shown in broken lines in Fig. 1) wherein it returns the slide into the slide changer 13.

As best shown in Fig. 2, the slider 21 protrudes through an elongated slot 23 of the base plate 16. The opposite ends 24 and 26 of the slot 23 define the limits of the path of the slider 21.

The slider 21 is secured to a reciprocably movable member, such as a flexible band or tape 27, that is suspended between and connected to rotatable driving elements, such as a first reeling drum 28 and a second reeling drum 29. There is also provided an idler drum 31, and the flexible tape 27 is suspended substantially straight between the idler drum 31 and the second reeling drum 29. The ends of the tape 27 are connected to the reeling drums 28 and 29, respectively.

The first reeling drum 28 is freely rotatably journaled on a rod 32 that is supported with relation from the plate 16, for instance by means of brackets 33. The drum 28 has a restricted portion on the external surface of which there is journaled freely rotatably a rotor, such as a gear wheel 34. To the drum 28 there is screwed, frontwardly of the wheel gear 34, a cam disc 36 that has a detent 37. On the front face of the gear wheel 34 there is pivoted about a pin 38 a latching member or latch 39 that has a long arm 41, and a short arm 42 that forms an angle with the long arm 41. The short arm 42 is so positioned and dimensioned that it can engage the detent 37 for coupling the gear wheel 34 with the cam disc 36 of the drum 28. A tension spring 43 has one end connected to the gear wheel 34 and the other end to the latch 39, and urges the latch 39 to turn in a direction D, tending to disengage the short arm 42 from the detent 37.

The long arm 41 carries near its free end a weight 44, and has an extension 46 that projects frontwardly of the face of the gear wheel 34.

A pinion 47 is freely turnably mounted on a source of rotary power, such as a shaft 48 of an electric motor 49. The pinion 47 meshes with the gear 34. An elastic frictional slip clutch or friction clutch 51 is provided between the motor shaft 48 and the pinion 47. It comprises a helical compression spring 52 that bears with one end against the front surface of a disc 53 that is secured to the shaft 48, and the spring 52 bears with its other end against the rear surface 54 of the pinion 47.

The motor 49 is so arranged that upon energization it will turn the shaft in the direction D. When the motor 49 is energized, the friction clutch 51 will couple the pinion 47 to turn with the shaft 48 in the direction D, and the pinion 47 will turn the gear wheel 34 in the direction C. Upon the attainment of a predetermined angular velocity, the centrifugal power will force the weight 44 outwardly, and cause the latch 39 to turn about the pivot 38 in the direction C, so that the short arm 42 will engage the detent 37, thereby coupling the gear wheel 34 to the drum 28 to turn the drum 28 in the direction C. The tape 27 will thereby be reeled-in by the drum 28, and will move the slider 21 in the direction A.

The engaging surfaces of the short arm 42 and the detent 37 are so arranged, relative to the position of the pin 38 and the axis of the cam disc 36, that they can be disengaged only upon the application of a force in excess of that of the spring 43, and will thus normally remain engaged.

To return the slider 21 in the direction B, the tape 27 will be reeled by the second reeling drum 29. The drum 29 is journaled for free rotation on a rod 56 that is supported on brackets 57 with relation to the plate 16. A helical spring 58, for instance made of music wire,

has one of its ends connected to a support 57 and the other end to the drum 29.

When the tape 27 is moved by the first drum 28 in the direction A, it will turn the drum 29 in the direction C. By this rotation of the drum 29, the spring 58 will be tensioned, and energy will be stored therein. When the motor 49 is de-energized, and thereby the motor driving applied to the first drum 28 ceases, the spring 58 will apply its stored energy to the second drum 29, and the drum 29 will turn in the direction D and will reel-in the tape 27 causing a movement of the slider 21 in the direction B. During the movement of the slider 21 in the direction B, the tape will rotate the first drum 28 in the direction D, and the cam disc 36 will turn the gear wheel 34 in the direction D, owing to the continued engagement of the detent 37 with the latch 39.

In order to release the latching engagement there is provided a release mechanism 61, which includes an arm 62. The arm 62 is so supported near the face of the gear wheel 34, that it will project into the path that the extension 46 describes when the latch 39 engages the detent 37. The arm 62 has an arcuate slot 63 through which there protrudes a stationary pin 64. Adjacent one of the long edges 66 of the arm 62, there abuts a stationary bar 67. A spring 68 urges the arm 62 into the position shown in Fig. 2.

When the latch 39 engages the detent 37 while the gear wheel 34 rotates in the direction C under the impulse of the motor 49, the extension 46 of the latch 39 will strike the arm 62 from below. Owing to the slot 63, the abutment bar 67, and the spring 68, however, the arm 62 will be pushed by the extension 46 into a position (shown in broken lines in Fig. 2) wherein the arm 62 clears the path of the extension 46.

When, on the other hand, the gear wheel 34 is turned by the drum 28 in the direction D under the impulse of the spring 58, the impact between the extension 46 and the arm 62 will cause the unlatching of the latch 39. When the gear wheel turns in the direction D, the extension 46 will strike the inner edge 65 of the arm 62, and the arrangement of the pin 64 and of the abutment bar 67 prevents any yielding of the arm 62. Instead, the latch 39 will yield and will turn about the pivot 38, disengaging the arm 41 from the detent 37 thereby causing uncoupling of the drum 28 from the gear wheel 34.

The motor 49 is connected to an electric source, indicated schematically by a battery 70, in a circuit which includes an operating switch 69.

Operation

The operation of the above described apparatus is as follows.

When the switch 69 is closed, the motor shaft 48 will revolve in the direction D. The friction clutch 51 will cause the pinion 47 to rotate with the shaft 48, thereby causing rotation of the gear wheel 34 in the direction C.

When a predetermined angular speed has been attained by the gear wheel 34, the weight 44 will cause the latch 39 to swing about the pin 38, and the arm 42 will engage the detent 37, coupling the gear wheel 34 with the cam disc 36 and thereby with the first reeling drum 28. Rotation of the reeling drum in the direction C will wind up the tape 27 onto the drum 28, causing movement of the portion of the tape 27 in the direction A. This movement of the tape 27 causes shifting of the slider 21 in the direction A, thereby moving the shiftable part 12 of the exemplified slide changer 13 in the direction A.

The movement of the slider 21 in the direction A ceases upon impact of the slider 21 with the edge 24 of the slot 23. At that instant, the shiftable part 12 of the slide changer 13 will be in the slide projecting position shown in solid lines in Fig. 1.

Slide changers of this type require that the full shifting force be applied substantially throughout the entire

stroke, yet free from any rebound at the end of the stroke.

The arrangement hereabove described in operation is sufficiently strong to carry the slider 21 with the shiftable part 12 throughout the path in the direction A. The friction clutch 51 will prevent any rebound upon impact of the slider 21 with the edge 24, as in that instant the pinion 47 will slip on the shaft 48.

While the switch 69 remains closed, the slider 21 will remain in the end position of abutment with the edge 24, as the friction clutch 51 tends to turn the pinion 47 in the direction in which it caused the movement of the slider 21 in the direction A.

During the movement of the slider 21 in the direction A, the tape 27 has rotated the second drum 29 in the direction C, thereby storing energy in the spring 58. Upon opening of the switch 69, the motor will stop, and thereby the force tending to turn the gear wheel 34 in the direction C will cease. Thereupon, the spring 58 will turn the second drum 29 in the direction D. During the beginning of the winding of the tape 27 onto the drum 29, under the impulse of the spring 58, the tape will turn in the direction D not only the first drum 28 but also the gear wheel 34 that is latched thereto and the pinion 47 that meshes with the wheel 34. The gear 34 turns the pinion 47 which owing to the strong force of the spring 52 turns the shaft 48 in the opposite direction than when energized electrically. During this movement, the slider 21 will be shifted in the direction B.

When the slider 21 has completed about one-half of the length of the return path, the extension 46 of the latch 39 will strike the arm 62 at the edge 65 causing the latch 39 to be turned about the pin 38 in direction D resulting in disengagement of the arm 42 from the detent 37. Thereby, the latch 39 is unlatched, and the gear 34 uncoupled from the first drum 28.

During the remainder of the movement of the slider 21 in the direction B, the tape 27 will pull only the drum 28, while the gear 34 and the pinion 47 will be coasting freely in the direction opposite to that when electrically energized. The movement of the slider 21 in the direction B will continue until the slider 21 strikes the opposite edge 26 of the slot 23. The spring 58 is strong enough to prevent any rebound, and to pull the load of the shiftable part 12 to the working position wherein the slide is positioned in registry with the optical axis of the projector (shown in solid lines in Fig. 1).

The arrangements of the friction clutch 51 and of the latch 39 offer several advantages. They permit the use of a comparatively weak motor 49, as the drum 28 will be engaged only after a sufficient amount of rotary energy has been stored in the gear wheel 34, which energy is reflected by the centrifugal force that is applied to the weight 44 of the latch 39. The friction clutch 51 renders possible not only the abutment of the slider 21 against the edge 24 free from any rebound, but also permits the slider 21 to come to rest in that abutment position adjacent the edge 24 while the motor 49 is running or stalling.

The motor 49 is merely strong enough to overcome the load of the shiftable part 12 and the force of the spring 58.

During the return trip of the slider 21, the energy that has been stored in the spring 58 is utilized. While springs have a force characteristic that decreases rapidly with decreasing deflection, the movement of the shiftable part 12 requires a pulling force that does not diminish towards the end. The arrangement of the latch 39 accomplishes this by reducing the load that the spring 58 needs to pull during the second half of the path of the slider 21, by uncoupling the drum 28 from the gear wheel 34 and pinion 47.

To operate the device, the operator will first close the switch 69 for movement of the slider 21 and theretofore of the shiftable part 12 in the direction A. By this

movement, a color slide is moved out from a position of registry with the optical axis of the projector 14. While the switch 69 remains closed, the color slide will be retracted. Upon opening of the switch 69, the slide 21 will be moved in the direction B into the optical projector axis.

For the exemplified use, it is important that the shifting takes place free from any rebound, as any rebound would move the color slide out-of-registry with either the optical axis of the projector 14 or the axis of the slide changer 13. The construction described in the foregoing prevents rebound in either end position of the slider 21.

I wish it to be understood that I do not desire to be limited to the exact details of construction shown and described, for obvious modifications will occur to a person skilled in the art.

Having thus described the invention, what I claim as new and desire to be secured by Letters Patent, is as follows:

1. In a reciprocable actuator device, in combination, a first reeling drum, a second reeling drum, and an idler drum, a flexible member suspended between said drums and being connected to said reeling drums and moving between said second reeling drum and said idler drum in a substantially straight path, said reeling drums being operable to reciprocate said member, said first reeling drum being freely journalled for rotation, a motor, control means between said motor and said first reeling drum operable for releasably coupling the motor therewith to move said member in one direction, said second drum being journalled freely turnably about an axis parallel to the axis of said first reeling drum and including a spring tensionable when said second reeling drum is moved by said member under the power of said motor, said spring being operable to return said member in an opposite direction upon de-energization of said motor, and means operable for releasing said control means to disengage said first reeling drum from said motor during the return movement of said member to reduce the driving load of said spring.

2. In a reciprocable actuator device, as claimed in claim 1, together with, an element connected to said member between said idler drum and said second reeling drum, whereby said element will be reciprocated in a substantially straight path as the motor is energized and de-energized, and stop means operable to limit the path of said element and thereby the movement of said member in either direction.

3. In a reciprocable actuator device, as claimed in claim 2, said control means comprising a shaft on said motor, a pinion journalled on said shaft, a gear wheel meshing with said pinion and journalled coaxially with said first reeling drum, centrifugally operative latching mechanism between said gear wheel and said first reeling drum operable to couple releasably said gear wheel with said first reeling drum upon the attainment of a predetermined angular velocity of said gear wheel when said gear wheel is driven from said motor, said latching mechanism being releasable when said gear wheel is driven from said second reeling drum, friction means between said motor shaft and said pinion, said motor and said friction means and said spring said gear wheel being so dimensioned that said element on said member will be arrested by said path limiting means in either direction free from rebound when said element of said flexible member is applied to a load for movement thereof in both directions.

4. In a reciprocable actuator device, in combination, a reciprocably movable member, and means for reciprocating said member comprising a rotatable first driving element connected to said member and operable to move it in one direction, a second rotatable driving element connected to said member and actuatable to return said

member in an opposite direction, a motor, control means including a slip clutch between said motor and said first driving element operable for releasably connecting said first driving element with said motor upon energization of said motor, said second driving element including resilient means and being operable for tensioning said resilient means when driven by said member as said member is moved in said one direction from said first driving element, said resilient means, upon de-energization of said motor, driving said second driving element in an opposite direction to return said member, the power of said resilient means being inferior to the power delivered by said first driving element when driven from said motor, whereby upon energization of said motor said member will be actuated in one direction against the force of said resilient means and, respectively, upon de-energization of said motor said member will be moved in the opposite direction by said resilient means, said motor including a shaft, said control means comprising a rotor 10 in driven connection with said motor shaft and driven thereby in one direction when said motor is energized, latching means actuatable centrifugally for latching said rotor with said first driven element upon the attainment of a predetermined angular velocity by said rotor to drive said first driving element from said rotor, and release means stationary with respect to said rotor and operable to engage said latching means to release it thereby unlatching said first driving element from said rotor to uncouple said first driving element from said motor during 20 rotation of said rotor in an opposite direction following de-energization of the motor.

5. In a reciprocable actuator device, as claimed in claim 4, said latching means comprising a lever pivoted to said rotor and including a weight and having a finger 35 and an extension, a detent connected to said first driving element, said finger being operable to engage said detent upon the application of centrifugal force of a predetermined magnitude on said weight, said release means including a resiliently suspended arm projecting 40 into the path of said extension as it rotates with the rotor around the axis thereof and being operable to yield upon impact by said extension during rotation of said rotor in one direction and, respectively, to engage said extension during rotation of said rotor in the opposite direction thereby disengaging said finger from said detent releasing the driving connection between said rotor and said first driving element.

6. In a reciprocable actuator device, having a source 50 of rotary power, in combination, a reciprocably movable member, means for oppositely driving said member comprising two rotatable elements spaced from each other and each in driving connection with said member, means for driving one of said elements including a control 55 mechanism operable to connect said one element to said source frictionally for driving said member in one direction and, respectively, for disconnecting it from said source during driving of said member in an opposite direction, the other element including resilient means operable to be tensioned by said member when it is moved in said one direction and, respectively, to drive said member in the opposite direction upon cessation of application 60 of said source energy, and means for energizing and de-energizing said source, said control means comprising 65 a wheel journalled coaxially with said one element and driven from said source, centrifugally actuatable latching means including a weighted latch pivoted to said wheel and a detent formed on said one element, said latch being operable to engage said detent upon the attainment of a predetermined angular velocity of said wheel in a direction whereby upon latching said one element will drive said one member in said one direction, and means operable for releasing said latch including a release member operable to be engaged by said latch during rotation 70 of said wheel in either direction and to yield upon impact 75

by said latch when said wheel turns in the direction driving said member, and to abut with said latch when said wheel turns in the opposite direction driven by said member thereby forcing said latch out-of-engagement with said detent.

7. In a reciprocable actuator device, having a source of rotary power, in combination, a reciprocably movable member, means for oppositely driving said member comprising two rotatable elements spaced from each other and each in driving connection with said member, means for driving one of said elements including a control mechanism operable to connect said one element to said source frictionally for driving said member in one direction and, respectively, for disconnecting it from said source during driving of said member in an opposite direction, the other element including resilient means operable to be tensioned by said member when it is moved in said one direction and, respectively, to drive said member in the opposite direction upon cessation of application of said source energy, and means for energizing and de-energizing said source, said source including a shaft, a motor rotating said shaft in one direction, said control means comprising a pinion journaled on said shaft, a gear wheel driven by said pinion, friction generating means between said shaft and said pinion sufficient for coupling said pinion with said shaft when

5 said shaft turns in said one direction, said pinion slipping on said shaft when rotated during shaft standstill and when braked during shaft rotation, and centrifugally operable latching means between said gear wheel and said one element operable to interconnect the same releasably during rotation of said gear wheel beyond a predetermined angular velocity in a direction whereby upon coupling said one element will move said member in said one direction.

10 8. In a reciprocable actuator device, as claimed in claim 7, together with, said gear wheel being journaled coaxially with said one element, means operable for releasing said latch during rotation of said gear wheel in an opposite direction, whereby when said one element is driven by said member from the power of said resilient means it will be uncoupled from said gear wheel to reduce the driving load of said resilient means.
